UNITED STATES PATENT OFFICE.

JAMES A. ST. CLAIR, OF BROKEN ARROW, OKLAHOMA, ASSIGNOR OF ONE-HALF TO
KNOX M. ROWE, OF BROKEN ARROW, OKLAHOMA.

MEASURING DEVICE.

Application filed September 20, 1921. Serial No. 501,918.

This invention relates to improvements in measuring devices and more particularly to such as are adapted for use in measuring the depth of oil, gas or drilled or partly drilled 5 wells,—the object of the invention being to provide simple means which may be readily placed in position and supported over the mouth of a well in such relation to the rope or cable which carries the bailer or other 10 weight, that the depth of the well may be accurately measured during the upward or downward movement of said rope or cable.

With this and other objects in view, the 15 invention consists in certain novel features of construction and combinations of parts as hereinafter set forth and pointed out in the claim.

In the accompanying drawings, Figure 1 20 is a view in elevation showing my improved device in position over the mouth of a well and illustrating its relation to the rope or cable. Figure 2 is a sectional view, and Figure 3 is a view showing the tension block and the supporting and adjusting means there- 25 for.

In Figure 1 of the drawing I have represented at 1 the mouth of the well and over this, a cover 2 may be placed, on which my improved measuring device is supported,— 30 said cover being of course provided with a suitable hole for the passage of the rope or cable 3 which carries a bailer or other part constituting a weight, at its lower end.

The device embodying my invention comprises two frame members 4—4 separated 35 from each other by a suitable spacing block and at one end, by a block 5 conforming in shape to the approximately triangular shape of the frame at this end. The angular block 40 5 is removably secured in place in the frame by means of screws or bolts 6 and through this block, a screw 7 is threaded and connected at one end with a tension block 8 through the medium of arch-springs 9, the 45 other or free end of said screw being provided with a suitable handle 10 for manipulating it. Bars 11 are secured at their respective ends to the frame members 4—4 respectively and between these bars, grooved 50 wheels 12—12 and 13 are mounted in position to engage the rope or cable 3. The tension block 8 carries grooved rollers 14 which are so positioned as to bear against the rope

or cable 3 between the grooved wheels 12 and 13 and in proximity to the former. 55

In order to permit the application of the device to the rope or cable, it is necessary to first remove the block 5 together with the tension block 8 and adjusting screw 7 and after the device shall have been applied to the rope or cable, these parts will be replaced. 60

The intermediate grooved wheel 13 is provided on each of its faces with a scale graduated in inches. The shaft 16 to which the intermediate wheel 13 is secured, is provided in its end, or rather in each end, with a notch 17, in which the driving member 18 of a register 19 enters. This register may be supported through the medium of suitable attaching means to one or the other of the 70 cross-bars 11.

It is apparent that suitable tension may be applied to the rope or cable 3 by manipulating the screw 7 and that the grooved wheels 14 of the tension bar 8 will so engage the rope or cable as to insure accurate co-operation of the intermediate wheel 13 therewith so that as the cable moves up or down the wheel 13 will be rotated so as to denote the number of inches traveled by the cable until the latter has moved one foot and then the co-operation of the wheel shaft 16 with the driving member of the register will cause the latter to register one foot and these operations will be repeated throughout the 85 length of travel of the cable from end to end of the well and the depth of the well will be indicated on the register. 80

In Figure 1 of the drawing I have shown the register so disposed that the depth of the well will be indicated thereon during the upward travel of the rope or cable. To adapt the device for measuring the depth of the well during the downward travel of the rope or cable, the register will be placed at 90 the opposite side of the device so that its driving member will engage in the notch at the other end of the wheel shaft 16. 95

Having fully described my invention what I claim as new and desire to secure by Letters-Patent, is:

In a well measuring device, the combination with a frame, of a driving wheel mounted in said frame and having journals accessible from both sides of the frame, guide 105 wheels mounted in said frame respectively

above and below said drive wheel, a tension device including a movable member and grooved rollers carried thereby to engage a cable passing over the guide wheels and the drive wheel, and a registering device adapted to be removably supported by the frame on either side thereof and having an operating part adapted for interchangeable

connection with either journal of the drive wheel, whereby measurement of the depth 10 of the well may be effected either during the descent or ascent of the cable.

In testimony whereof, I have signed this specification.

JAMES A. ST. CLAIR.
